ALANSON P. BRUSH AND OWEN M. NACKER, OF DETROIT, MICHIGAN.

INTERNAL-COMBUSTION ENGINE.

Application filed August 13, 1920. Serial No. 403,183.

To all whom it may concern:

Be it known that we, ALANSON P. BRUSH and OWEN M. NACKER, both citizens of the United States of America, residing at Detroit, in the county of Wayne and State of Michigan, have invented certain new and useful Improvements in Internal-Combustion Engines, of which the following is a specification, reference being had therein to the accompanying drawings.

The modern internal combustion engine of the 4-cycle type, when adapted to service which requires a wide range of speed and power output, is ordinarily controlled principally by throttling the amount of mixture of air and fuel supplied to the combustion chambers.

An engine of this type, when used for this kind of service, as for example the modern motor vehicle, has several undesirable characteristics. Among them are:

First—The tendency to suck lubricating oil past the pistons into the combustion chambers when the controlling throttle is nearly closed. This is due to the comparatively high vacuum on the suction strokes under the conditions outlined, and is commonly called "oil pumping."

Second—if an engine of this type is provided with sufficient cooling means to maintain it at proper operating temperature when it is producing high power outputs, it cools down below proper operating temperature when running with a nearly closed throttle for low power outputs.

Third—Because of the undesirable low temperature of the engine when operating at low power outputs, there is apt to be a failure both in the manifold and in the combustion chambers of the engine to vaporize some of the fuel supplied to the engine with the result that such unvaporized fuel is not completely burned, resulting in a waste of fuel and in the contamination of the lubricating oil by such unvaporized fuel, finding its way past the pistons into the crankcase of the engine.

This difficulty of unvaporized fuel is further aggravated in a multiple cylinder engine, because of the low air velocity in a manifold supplying several cylinders from one carburetor—some cylinders receive more fuel than others—and permits an accumulation of fuel within the manifold, when the engine is operating with a nearly closed

throttle, which accumulation of fuel is thrown into the combustion chambers of the engine when the throttle is opened.

Fourth—In a multiple cylinder engine involving the use of a manifold to supply the several cylinders with fuel and air mixture from one carburetor, if the manifold is large enough to supply an adequate amount of mixture to the several cylinders for high power outputs at high speed, then when operating with a nearly closed throttle for low power outputs or low speeds, the air velocity within the manifold becomes too low to permit the manifold to function with fuels of low volatility; that is, with fuels that do not entirely vaporize before introduction to the cylinders.

The present invention overcomes these difficulties by a simple modification, which consists essentially in means for introducing a small portion of the exhaust gases into the intake in proportion to the restriction thereof. The gases so introduced have the effect; first, of diminishing the high vacuum and reducing the tendency to suck oil past the pistons; second, the heat of the introduced gases will partly compensate for the lowered heat generation and tend to maintain more uniform temperature conditions in the engine cylinders—it will also assist in the vaporization of the liquid fuel in the manifold; third, the velocity of the gases passing through the manifold is increased by the added volume of gas, which lessens the tendency for the liquid to fall out of suspension.

Our invention may be embodied in various constructions, but in the drawings it is shown more or less diagrammatically, in which—

Figure 1 is a section through an internal combustion engine; and

Figure 2 is a cross-section through the intake and exhaust conduits, showing a modified construction.

A is the combustion chamber of an internal combustion engine, B is the intake passage controlled by the valve C, and D is the exhaust passage controlled by the valve E. F represents diagrammatically a carburetor having the fuel jet G, and H is the throttle. Our invention is applied to the engine by a simple by-pass connection I between the exhaust conduit and intake, the point of attachment to the latter being preferably before the first sub-division of the manifold and preferably adjacent to the

throttle on the vacuum side thereof. This by-pass is controlled by a valve J, which as shown in Figure 1 is mechanically connected with the throttle through the rock arms K 5 and L and the connecting link M. The construction is such that when the throttle is moved from open to closed or idling position, the valve J will be correspondingly moved from closed to open position. Thus, 10 the amount of exhaust gases introduced is varied according to the position of the throttle and, as before stated, will tend to reduce the high vacuum to increase the velocity of the gases in the manifold and will modify 15 extreme variations in temperature.

With the modified construction shown in Figure 2, in place of a mechanical connection between the valve controlling the by-pass and the throttle, an automatically operating valve is substituted. This, as shown, 20 consists of a piston valve N having its outer end exposed to atmospheric pressure and its inner end exposed to the pressure of the intake manifold. O is a port through 25 the valve adapted for registration with the by-pass I, and P is a spring for yieldably pressing the valve outward into a position where the port O is closed. P' is a stop for limiting the stroke of the piston valve. 30 Thus, in operation, whenever the vacuum in the intake manifold is increased, the valve N will be moved towards open position, which will admit exhaust gases into the intake. 35 As above stated, the advantages of introducing a variable quantity of inert gas into the combustible mixture are, first, that the vacuum in the cylinder is reduced, thereby avoiding the sucking in of oil; second, the 40 velocity of the gases passing through the intake manifold, particularly in a multi-cylinder engine, will be increased, which will prevent the falling out of the fuel from sus-

pension. The inert gases may be introduced at any point to obtain the first advantage, 45 but for the second they should be introduced before the first sub-division of the manifold. Preferably, these inert gases are introduced on the vacuum side of the throttle, but an advantageous effect could also be produced 50 by introducing them upon the atmospheric side of the throttle—but on the engine side of the fuel inlet. In other words, to avoid interfering with the function of the carburetor, and the proper proportioning of the 55 fuel to the air, the inert gases must be introduced on the engine side of the fuel inlet.

What we claim as our invention is:

1. The combination with an internal combustion engine, including intake and exhaust 60 conduits, of a throttle controlling the intake conduit, a by-pass connection between the exhaust conduit and intake conduit connecting with the latter adjacent to said throttle on the engine side thereof, a valve for controlling said by-pass, and a mechanical connection between said valve and throttle by which the by-pass is opened as the throttle is closed.

2. The combination with an internal combustion engine including intake and exhaust conduits, of a throttle controlling the intake conduit, a by-pass connection between the exhaust conduit and intake conduit connecting with the latter adjacent to said throttle 75 on the engine side thereof, a rotary valve for controlling said by-pass, an arm connected to said valve, a second arm connected to said throttle, and a link connecting said arms whereby the by-pass is opened as the 80 throttle is closed.

In testimony whereof we affix our signatures.

ALANSON P. BRUSH.
OWEN M. NACKER.
